CLAIM

The ornamental design for a magnetic septum nose ring, as shown and described.

DESCRIPTION

FIG. 1 is a perspective view of a magnetic septum nose ring showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the magnetic septum nose ring.

The broken lines in the drawings depict portions of the magnetic septum nose ring that form no part of the claimed design.
